UNITED STATES PATENT OFFICE.

RUSSELL K. COLLINS, OF FORT WORTH, TEXAS, ASSIGNOR, BY DIRECT AND MESNE ASSIGNMENTS, TO COLLINS PROCESS, INC., OF WILMINGTON, DELAWARE, A CORPORATION OF DELAWARE.

CONVERSION APPARATUS FOR REFINING HYDROCARBON MATERIALS.

Application filed May 18, 1922. Serial No. 561,925.

This invention relates to a novel expanding and converting apparatus to facilitate the refining of hydro-carbon materials according to the process defined and claimed 5 in my co-pending application, Serial No. 563,136, filed May 23, 1922.

The primary object of this invention is the provision of an expander adapted to receive hydrocarbon vapors from a distilled 10 body of hydro-carbon liquid, and separating the vapor from the liquid in order that the former may be treated according to the chemical, thermodynamic, and mechanical laws of physical conversion.

15 A further object of the invention is the provision of an expander of a novel design, adapted to receive a relatively large body of vaporized hydro-carbon material in such manner as to provide for the uniform heating of the body of vapor in order to convert the same for releasing the constituent parts thereof.

20 A further object of the invention is the provision of a back trap convertor adapted to receive a heavier fraction of converted and condensed hydro-carbon material for novel treatment to revaporize and refine the same.

25 A further object of the invention is the provision of an expander and back trap convertor cooperating in such manner as to utilize the same products of combustion for the heating thereof.

30 A further object of the invention is the provision of an expander and back trap convertor adapted to respectively receive a pre-expanded hydro-carbon vapor and a heavier fraction of a hydro-carbon for destructive distillation thereof, and combining the revaporized fraction with the initial hydro-carbon vapor in such manner as to increase the yield of a desired distillate.

35 Other objects and advantages will be apparent during the course of the following 40 description.

In the accompanying drawings, forming a part of this specification, and wherein similar reference characters designate corresponding parts throughout the several views.

45 Figure 1 is a side elevation, partly in section, showing the relative arrangement of the parts of the improved conversion apparatus.

Figure 2 is a transverse cross sectional view, taken on the line 2-2 of Figure 1. 55

Figure 3 is a transverse cross sectional view, taken on the line 3-3 of Figure 1.

Figure 4 is a longitudinal cross sectional view, taken through the back trap convertor. 60

Figure 5 is a transverse cross sectional view, taken on the line 5-5 of Figure 4.

Figure 6 is a transverse cross sectional view, taken on the line 6-6 of Figure 4. 65

In the drawings, wherein for the purpose of illustration is shown the preferred embodiment of this invention, the letter A designates the improved apparatus, which includes a furnace B; expander C; and back trap convertor D. 70

The furnace B is of any preferred type, including the chamber 10, which is provided with an opening 11 therein for access of heat to the expander and back trap convertor.

Flues 12 are preferably provided in the furnace B, cooperatively positioned with respect to the passageway 11, said flues being provided for the purpose of controlling the flow of the products of combustion for the purpose of heating the expander C and back 75

trap convertor D.

Referring to the expander C, the same preferably includes a cylindrical shaped casing 15, which is vertically positioned and includes the side walls 16; top wall 17; and bottom wall 18. 80

A pipe 19 is disposed in an inlet opening 19^a adjacent the bottom wall 18 for the supply of pre-expanded hydro- 85

carbon vapors to the chamber 20, the vapor so supplied to the chamber 20 being produced in a vaporizing still, substantially as described in my co-pending application

above referred to. The casing 15 is mounted upon a frusto-conical shaped housing 21, which provides a heat chamber 22 below the bottom 18 of said casing, said housing 21

likewise being provided as a support for the back trap convertor D in a manner which will be more fully described hereinafter.

The housing 21 is so positioned that the heat chamber 22 therein is in communication with the passageway 11 of furnace B, in order to receive products of combustion therefrom. The casing 15 may be secured in any appropriate manner to the top of the hous- 95

ing 21 so that the same is vertically posi-

tioned, substantially as is illustrated in Figure 1 of the drawings.

Tubes or flues 25 are provided in the chamber 20 of the casing 15, arranged in parallel relation longitudinally thereof, and supported at their ends by the top and bottom plates 17 and 18 respectively of said casing 15 so that said tubes open at their lower ends into the chamber 22 of the housing 21, 10 and at their upper ends into the chamber 27 of a stack 28. Perforated nickel screens 29 are provided in the chamber 20 arranged in spaced parallel relation with respect to the top and bottom walls 17 and 18, and suitably affixed circumferentially thereof to the 15 inside of the casing wall 16, so that the chamber 20 is subdivided into a plurality of compartments. The screens 29 are preferably of nickel, so that the same may have 20 catalytical reaction upon the hydrocarbon product which occupies the chamber 20. A conduit 30 is preferably disposed in an outlet opening 30^a adjacent the top wall 17 of the expander casing 15, for the purpose of 25 conveying vapors from the chamber 20 after the desired conversion therein, for condensing purposes as will be understood by those skilled in the art to which this invention pertains.

30 Referring to the back trap convertor D, the same includes a cylindrical elongated casing 40, transversely mounted in the housing 21 of the apparatus A, so that the pointed ends 41 and 42 thereof extend exteriorly of 35 said housing 21, although the main body portion 43 of the casing 40 is disposed within the heating chamber 22. The chamber 45 of the casing 40 is adapted for receiving a condensed fraction from the ordinary de- 40 phlegmator (not shown) through a drain tube 46, which is in communication with the chamber 45 at the extreme end of the casing 40. A pipe section 47 is detachably mounted in the screw threaded opening 48^a of the casing end 41, and extends interiorly of the casing 45; having an elbow 48 mounted upon the free end thereof, and whereby the condensed fraction may flow from the drain pipe 46 through the pipe 47 and elbow 48 50 to be deposited in the chamber 45, as can be well understood.

A pipe line 50 preferably communicates with the convertor chamber 45 adjacent the inlet pipe section 47; said inlet pipe 50 being 55 provided for leading "fixed" hydro-carbon gases into the convertor D for combination with the hydro-carbon product therein. Superheated steam may likewise be conveyed from any suitable source (not shown) into 60 the chamber 45 through an inlet conduit or pipe 52, at an end of the convertor casing 40 opposite that end in which the "fixed" gases and hydro-carbon fraction inlet. A pressure gauge 53 may be detachably mounted upon 65 the end 42 of the casing 40, to determine

the internal pressure in the chamber 45. If desired, a drain tube or cock 54 may be provided in the lower portion of the casing 40 upon the end 42 thereof, for drain of residue hydro-carbon products and for cleaning purposes. Likewise a manhole (not shown) could be placed in the casing end 42 for cleaning and inspection purposes, although such provision is not absolutely necessary. The chamber 45 is preferably provided with 70 a plurality of perforated flat baffle plates 55 arranged therein in staggered relation, so that the flow of materials within said chamber is baffled, pursuing a tortuous path in order that the proper combination and reaction of said materials may take place. A perforated tubular shaped nozzle 57 is provided, detachably mounted in the top of the casing 40 intermediate the ends 41 and 42, the same being provided for egress of the 75 hydro-carbon products issuing from the chamber 45 after the same has been vaporized. It is preferred that a perforated nipple 58 be provided in the perforated tube 57 at the juncture thereof with the casing 40. The top 59 of the nozzle 57 is perforated, and in lieu thereof a cap may be provided. The baffle plates 55 are preferably all of the same formation, being segmental to have a 80 marginal edge 60 thereof struck from a center which will lie in the longitudinal axis of the casing 40 when said marginal edges 60 of the baffle plate 55 are affixed to the interior circumference of the chamber 45. The remaining marginal edge portion 61 is struck from a point off center with respect to the arc from which the other marginal edge portion 60 of the plate 55 is struck, so that when 85 each of the baffle plates 55 is positioned within the casing 40, the edge 61 will be free of contact with the casing 40, to provide a relatively large passageway 62 whereby the material in the casing 40 may flow from one side of a baffle plate 55 to the other, without 90 necessity of flowing through the perforations 63 of said baffle. A rod 65, preferably of some non-corrosive material may be disposed longitudinally through the casing 40 and fixed at one end to the elbow 48, and at its 95 opposite end disposed within a socket 66; said rod 65 being provided for supporting the ends of each of the baffle plates 55 adjacent the marginal edge portions 61, as can 100 be well understood from Figure 4 of the drawings. This rod 65 may, however, be dispensed with, and the baffles 55 attached by other means, such as by riveting, to the 105 casing 40.

The back trap convertor D is assembled to the expander C in a manner above described, and in this position, the perforated nozzle 57 extends through the bottom wall 18 of the expander C into the chamber 20 thereof, so 110 that vapors issuing from the back trap convertor arise into the chamber 20 and asso- 115 120 125 130

ciate with the vapors therein which have been supplied through the vapor line 19.

The process and remaining apparatus with which the improved expander and back trap convertor are used, are fully described and claimed in my copending application Serial No. 563,136, filed May 23, 1922, and need only be incidentally mentioned to show the co-operation which the expander and back trap convertor has therewith. The free expanded vapors entering the chamber 20 through the vapor line 19 spiral upwardly about the flues 25 in violent manner, and are uniformly heated and expanded, both mechanically and thermally in the quickest manner possible, until the expanding capacity of the vapor molecules causes them to burst and conversion takes place, releasing the lighter and more volatile constituents from the heavier constituent parts thereof. The released constituent parts of the vapor, after conversion, exit from the expander C into the line 30, after which the same enter a dephlegmator (not shown). After separation of the heavier fractions by condensation, the same are led into the chamber 45 of the back trap convertor D through the inlet pipe 46. In this chamber 45, the "fixed" gases entering from the line 50 are baffled, and admixed with the liquid hydrocarbon. The heavier distilled fraction in the back trap convertor is also associated with the hydrogen released from the superheated steam which is injected therein through the conduit 52, and the materials thus placed in the casing 40 of the back trap convertor D are thoroughly heated, by means of the positioning of the back trap convertor D in the path of the heated products of combustion as hereinbefore mentioned. The vapor arising from the agitated materials within the back trap convertor D enters the expander chamber 20 and therein cooperates with the vapor issuing from the vapor line 19. The process of conversion of all vapors is finally effected within the chamber 20 of the expander C. The reactions taking place within the chamber 20 are of such character as to produce a maximum yield of the desired fractions.

It is to be noted that the back trap convertor D performs a function which is essentially that of a small rerun still, but of greatly increased efficiency over the ordinary rerun still, particularly in that its fraction ingredient is delivered in relatively small quantities from the dephlegmating tower, for treatment and vaporizing in continuous cooperation with the expansion process, so that not only an improved product is obtained, but a greater yield of the desired fraction is provided in an economical manner, by reason of the cooperative association of the expander C and back trap convertor D. No mechanical stirrers or coke removers

are needed in the apparatus, as no total decomposition of the hydrocarbon product takes place, except at the will of the operator. For cleaning and inspection purposes, a man hole may be provided, in any suitable location in the expander casing 15.

From the foregoing, it can be seen that an improved apparatus has been provided, whereby hydro-carbon products may be truly converted in their separated vaporized states, in a manner, and by such apparatus which takes into consideration the laws by which conversion is naturally governed. It is to be noted that the expander C and back trap convertor D cooperate, not only in the manner in which the products therein are heated from the same products of combustion, but whereby the vapors arising from the back trap convertor D may cooperate with the vapors of the initial material applied to the expander C by the vapor line 19, so that the hydro-carbon products are treated in the best possible manner.

Various changes in the shape, size and arrangement of parts of the apparatus herein shown and described, for the refining of various hydro-carbon materials may be made without departing from the spirit of this invention or the scope of the claims.

I claim:

1. As an article of manufacture, a cylindrical shaped expander including a casing having side, top and bottom walls, spaced flues mounted longitudinally within the chamber of said casing opening at the ends thereof outwardly of the top and bottom walls, said casing having inlet and outlet openings disposed respectively adjacent the bottom and top walls thereof, and perforated nickel baffle plates disposed within the chamber of said casing intermediate the inlet and outlet openings thereof.

2. As an article of manufacture, a unit for the treating of hydro-carbon products comprising an elongated casing having a treating chamber therein, inlet means in one end of said casing for admitting a hydrocarbon liquid and gas within said chamber, inlet means disposed in the other end of said chamber for admission of superheated steam into said chamber, a perforated tube extending upwardly from said casing and having communication therewith intermediate the ends of the casing, means for heating the casing and baffle plates arranged in the treating chamber of said casing, each having certain edges thereof spaced from the circumference of the chamber to provide a passageway thereby, said passageways being disposed in staggered relation intermediate the inlet means in said casing and the outlet tube in said casing, so that materials being treated therein will, of necessity, pursue a tortuous path therethrough.

3. In a device of the class described, the

combination of heating means, a housing disposed over said heating means including a chamber for receiving the heat from said heating means, an expander carried by said 5 housing including a chamber having inlet and outlet openings therein, said chamber being provided with flues extending longitudinally therethrough and opening outwardly at their ends for receiving heat from 10 said housing for conduction therethrough for heating the contents of said expander chamber, and a convertor unit mounted transversely through said housing to have a portion disposed in the heat chamber of 15 the housing, said convertor having inlet and outlet openings therein whereby a product after treatment in said convertor may arise into the chamber of said expander, said convertor and expander being so positioned 20 upon said housing as to be heated by the same products of combustion arising from said heating means.

4. In apparatus of the class described a vertically disposed expander receptacle having 25 a compartment and including a bottom wall and having inlet and outlet openings to the compartment thereof, an elongated converter receptacle horizontally supported below the expander receptacle and including 30 a vertically disposed tube extending through the bottom wall of the expander receptacle into the compartment thereof, said converter receptacle having a hydrocarbon inlet opening therein remote from said vertically disposed tube, and means for heating the 35 converter and expander receptacle from the

same products of combustion whereby to vaporize hydrocarbon in the converter receptacle so that the vapor thereof will pass through said tube into the compartment of 40 said expander receptacle.

5. An apparatus of the class described comprising an expander having inlet and outlet openings communicating with a compartment therein, vertical flues extending 45 thru said compartment in uniform arrangement, a rerun chamber having inlet openings therein and an outlet opening communicating with the compartment of said expander, and means for heating said rerun unit 50 and expander with the same products of combustion which pass through the flues of said expander for uniformly heating the product therein.

6. An expander for receiving hydrocarbon products comprising a casing including top and bottom walls, spaced heat conducting flues extending through the casing between the top and bottom walls and supported by said top and bottom walls, said casing having inlet and outlet openings for the compartment between the top and bottom walls, and spaced baffle plates disposed in the casing between said top and bottom walls and having the hydrocarbon inlet and outlet openings disposed at opposite sides thereof, said baffle plates each having minute perforations therein for the flow of hydrocarbon products therethrough from the inlet opening to the outlet opening of said casing.

RUSSELL K. COLLINS.
